UNITED STATES PATENT OFFICE.

FEDERICO ALESSI, OF NEW YORK, N. Y.

PROJECTILE.

SPECIFICATION forming part of Letters Patent No. 668,618, dated February 26, 1901

Application filed August 1, 1900. Serial No. 25,598. (No model.)

To all whom it may concern:

Be it known that I, FEDERICO ALESSI, a subject of the King of Italy, residing at New York, in the county of New York and State of New York, have invented certain new and useful Improvements in Projectiles, of which the following is a full and complete specification, such as will enable those skilled in the art to which it appertains to make and use the same.

This invention relates to ordnance projectiles; and the object thereof is to provide a shell of this class which possesses great explosive power and improved means for producing the explosion thereof when the shell strikes a ship or other object; and with this and other objects in view the invention consists in an ordnance projectile or shell constructed as hereinafter described and claimed.

The invention is fully disclosed in the following specification, of which the accompanying drawings form a part, in which the separate parts of my improvement are designated by the same reference characters in each of the views, and in which—

Figure 1 is a longitudinal section of a shell constructed according to my invention, and Fig. 2 a cross-section thereof on the line 2 2.

In the practice of my invention I provide a shell 5 of the usual form, said shell being conical at one end, as shown at 6, and cylindrical at the other, as shown at 7, and within the shell is a conical-shaped space or chamber 8, the form of which is similar to that of the shell, the said space being closed by an end cap 9; which is screwed into the cylindrical end of the shell, as shown in Fig. 1.

Extending backwardly from the point of the shell, centrally of the inner space thereof and formed integrally with the shell, is a tube 10, which connects with a cross-bar or cross-head 11, by means of a conical portion 12, and said conical portion 12 is hollow and communicates with the central bore 13 of the tube 10, and the said central bore 13 of the tube 10 is extended and opens outwardly through the point of the shell, as shown at 14.

The base of the conical portion 12 of the tube 10 is directed rearwardly, and secured transversely of the shell in line with and adjacent to the cross-bar 11 is a supplemental cross-bar or cross-head 15, which is preferably secured in place by screws or bolts 16,

and between the supplemental cross bar or head 15 and the cross bar or head 11 is a transverse space 17, in which are mounted 55 radially-movable bolts 18. A bolt 19 is also placed in the tube 10 and projects forwardly through the point of the shell, as shown at 20, and the inner end thereof is pivotally connected with two links 21, each of which 60 is pivotally connected with a short supplemental link 22, and the links 22 are pivotally connected with the bolts 18, as clearly shown in the drawings.

Formed in the cross head or bar 11 at the 65 opposite sides of the conical inner end of the tube 10 are two holes or openings 23, in which are placed percussion-caps 24, and the bolts 18 are provided adjacent to their pivotal connections with the supplemental links 22, each 70 with a forwardly-directed projection 25, and said bolts at their outer ends each with a cylindrical head 26, and these heads fit in and are adapted to move in transverse radial bores 27, formed in the body of the shell and in radial line with and in communication with the space 17, in which the bolts 18 are mounted.

The interior of the shell is filled with any suitable highly-explosive material adapted to be ignited and exploded by the percussion-caps 24, and the operation will be readily understood from the foregoing description when taken in connection with the accompanying drawings and the following statement thereof.

Suppose a shell to be fired at the side of the 85 ship provided with armor-plate. The moment the point of the shell strikes the side of the ship the bolt 19 is driven inwardly and the point of the shell penetrates the side of the ship. At the same time the bolts 18 are driven 90 out radially from the sides of the shell and the percussion-caps 24 are ignited by the projections 25 and the shell is exploded. The heads 26 of the bolts 18 are at the same time driven outwardly and coming in contact with the armor-plate of the ship retard the passage of the shell therethrough, and the explosion occurs before the shell passes through the side of the ship, and instead of making a hole through the side of the ship large enough 95 for the shell to pass through the side of the ship or a large portion thereof will be blown out.

The bolts 18 and the heads 26 thereof may

be made of any desired transverse thickness, and said bolts are simply intended to retard the passage of the shell through any thing or object which may be struck thereby in order to cause the explosion of the shell as it passes through said object.

It will be seen that the angle at which the links 21 are connected with the supplemental links 22 and with the bolt 19 is such that when the bolt 19 is driven inwardly the bolts 18 will be projected through the sides of the shell only far enough to accomplish the result hereinbefore set out, and it will be apparent that changes in and modifications of the construction herein described may be made without departing from the spirit of my invention or sacrificing its advantages.

Having fully described my invention, I claim as new and desire to secure by Letters Patent—

1. A shell which is conical at one end, and provided at the other with a removable head or closure device, said shell being provided centrally of the conical end with a tube which extends rearwardly and is in connection with a transverse head secured in the shell, said transverse head being provided with a transverse passage in communication with said tube, and the central bore of said tube being projected through the conical point of the shell, and a bolt mounted in said tube and projecting through the point of the shell, the inner end of said bolt being connected by means of pivoted links with transversely movable bolts mounted in said head and adapted to be projected through the sides of the shell, substantially as shown and described.

2. A shell which is conical at one end, and provided at the other with a removable head or closure device, said shell being provided centrally of the conical end with a tube which extends rearwardly and is in connection with

a transverse head secured in the shell, said transverse head being provided with a transverse passage in communication with said tube, and the central bore of said tube being projected through the conical point of the shell, and a bolt mounted in said tube and projecting through the point of the shell, the inner end of said bolt being connected by means of pivoted links with transversely movable bolts mounted in said head and adapted to be projected through the sides of the shell, said bolts being also adapted to explode the shell, substantially as shown and described.

3. A shell which is conical at one end, and provided at the other with a removable head or closure device, said shell being provided centrally of the conical end with a tube which extends rearwardly and is in connection with a transverse head secured in the shell, said transverse shell being provided with a transverse passage in communication with said tube, and the central bore of said tube being projected through the conical point of the shell, and a bolt mounted in said tube and projected through the point of the shell, the inner end of said bolt being connected by means of pivoted links with transversely movable bolts mounted in said head and adapted to be projected through the sides of the shell, said bolts being also adapted to explode the shell, by means of caps set in said transverse head and projections formed on said transversely movable bolts, substantially as shown and described.

In testimony that I claim the foregoing as my invention I have signed my name, in presence of the subscribing witnesses, this 28th day of July, 1900.

FEDERICO ALESSI.
